UNITED STATES PATENT OFFICE.

ERNEST RIEDER, OF LAKE FOREST, ILLINOIS.

MORTISING-MACHINE.

1,251,579.

Specification of Letters Patent.

Patented Jan. 1, 1918.

Application filed June 12, 1914. Serial No. 844,782.

To all whom it may concern:

Be it known that I, ERNEST RIEDER, a citizen of the United States, residing at Lake Forest, in the county of Lake and

5 State of Illinois, have invented certain new and useful Improvements in Mortising-Machines, of which the following is a specification.

This invention relates to boring or sawing 10 machines and more particularly to a device of this nature which embodies an endless belt or chain of cutting blades for mortising or cutting substantially rectangular holes or openings in boards or timbers.

15 An object of this invention is the provision of a machine of this nature wherein the supporting or bracing legs are resiliently connected to the sawing or cutting parts of the machine so that the incision of the cutting blades into the timber may be more finely regulated and adjusted by manual pressure and also so that the cutting blades will be held out of engagement with the timber unless pressure is applied thereto.

20 Another object of this invention is the provision of means for regulating the tension of the belt which carries the cutting blades.

25 With the foregoing and other objects in view, this invention consists in such novel features of construction, combination and arrangement of parts as will be hereinafter more fully described, illustrated in the accompanying drawings and claimed.

30 In describing the invention in detail, reference will be had to the accompanying drawings wherein like characters of reference designate like or corresponding parts throughout the several views, and in which—

35 Figure 1 is a side elevation of the improved mortising machine showing parts thereof broken away,

Fig. 2 is a side elevation of the mortising machine, parts being broken away,

40 Fig. 3 is a detail view of a part of the means for regulating the tension of the blade carrying belt,

Fig. 4 is a plan view of a part of the bracing or supporting legs structure,

45 Fig. 5 is a central sectional view through the handle of the mortising machine,

Fig. 6 is a central sectional view through the handle of the mortising machine showing the opposite half to that shown in Fig. 5,

50 Fig. 7 is a detail perspective view of one of the cutting blades,

Fig. 8 is a plan view of one of the cutting blades, and

Fig. 9 is a detail view of one of the side blades used in the present invention. 60

Referring more particularly to the drawings, 1 designates a block which has a rod 2 depending therefrom. The rod 2 has a bearing block 3 removably attached to its lower end, which bearing block has its lower end 65 bifurcated as at 4, (see Fig. 2) forming arms 5 and 6, which have the pulley 7 seated therebetween. Each of the arms 5 and 6 are provided with slots 8 which have the ends of the shaft 9 slidably seated therein. 70 The shaft 9 has the pulley 7 rotatably mounted thereupon.

A second pulley 10 is rotatably mounted upon a shaft 11, which shaft is carried by the upper end of the block 1. A belt 12 75 passes about the pulleys 7 and 10 and carries a plurality of cutting blades 14 upon its outer surface. The cutting blades 14 are shown in the drawings as being formed of two substantially triangularly shaped sections joined together and having their edges beveled, as is clearly shown in Figs. 7 and 8 of the drawings. The cutting blades 14 are removably attached to the belt 12 so that when one of them becomes broken, worn out 85 or dull, it may be removed and a good blade substituted in lieu thereof. The cutting blades 14 are secured to the belt 12, so that the apex of the triangular sections or the pointed ends will enter the timber being 90 mortised upon operation of the machine.

The shaft 11 has a gear-wheel 15 mounted upon its outer end, which meshes with a second gear 16. In the drawings, the gear 16 is shown of much greater diameter than 95 the gear 15, so as to increase the speed of travel or the number of revolutions of the gear 15 with respect to the number of revolutions of the gear 16. The gear 16 is rotatably mounted upon a shaft 17 which is 100 carried by the block 1 and it has a handle 18 secured thereto by bolts 19. The bolts 19 are attached to the handle 18 and the gear 16 in spaced relation, so as to prevent pivotal movement of the handle during the 105 operation of the same.

A handle 20 which is preferably constructed of resilient material such as sheet metal is secured to the block 1 having its upper end formed so as to be conveniently gripped by 110 the hand of the person operating the device. The handle 20 has depressions 21 formed

upon the edge of its ends, which edges are bent to engage the sides of the block 1, as is shown in Fig. 2 of the drawings, and the handle is secured to the block in any suitable manner, such as by screws, nails or the like, and by the frictional engagement between the ends of the handle and the block 1.

The rod 2 is slidably mounted in an opening 22 which is formed in a bar 23. The bar 23 has its ends bifurcated as at 24, and supporting or bracing legs 25 are pivotally connected to the bifurcated ends 24 by means of bolts 26, as is clearly shown in Fig. 4 of the drawings. The rod 2 has a spring 27 wound thereabout, one end of which spring engages the lower end of the block 1, and the other end of which engages the bar 23 and presses downwardly upon the block, causing the bearing block 3 which is connected to the lower end of the rod 2 and the parts carried thereby, to be normally held out of engagement with the timber which is to be mortised, when pressure is not applied to the handle 20, or normally holding the bearing block and the parts carried thereby in the position which is shown in Fig. 2 of the drawings.

The tension of the belt 12 is regulated by adjusting screws 28 which are mounted in the bearing block 3 and have their lower ends engaging the shaft 9. By various adjustments of the pins 28, the tension of the belt 12 is regulated and the position of the shaft 9 in the slots 8 also regulated.

35 The side teeth or blades 29 provide for an accurate cutting of square holes, since by depending entirely upon the blades 14, two of the opposite side of the holes or openings which would be cut by the machine, would 40 be slightly beveled or inclined, in view of the formation of the blades 14, whereas by the provision of these teeth or blades 29, an accurate mortising of the timber will be assured.

45 When it is desired to cut an opening or a substantially rectangularly shaped mortise or hole in a timber, the mortising machine which has heretofore been described is positioned so that the supporting legs 25 will 50 engage the surface of the timber in which the opening is to be made. The spring 27 will hold the cutting teeth 14 which are mounted upon the outer surface of the belt 12 out of engagement with the timber, as is 55 clearly shown in Fig. 2, until pressure is applied to the handle 20. When pressure is applied to the handle 20, it forces the rod 2 downwardly, and consequently the pulleys 7 and 10 and the belt 12, causing the teeth 14 to bite into the timber. The rotation of 60 the belt through the medium of the handle 18 and the gears 15 and 16 will operate the

belt about the pulleys 7 and 10 causing the cutting teeth to cut into the wood and also to carry the shavings or cuttings up and out 65 of the opening which is being formed. Continued pressure upon the handle 20 will cause the blades to cut deeper into the wood and the depth of the holes or openings which are being cut may be regulated.

70 From the foregoing description taken in connection with the accompanying drawings, the advantages of the construction and of the method of operation of the improved mortising machine will be readily apparent 75 to those skilled in the art to which this invention appertains and, while in the foregoing description, the principle of the operation of this invention has been described together with various features of construction, 80 it is to be understood that certain minor features of construction, combination and arrangement of parts may be altered to suit practical conditions provided such alterations are comprehended within the scope of 85 what is claimed.

What is claimed is:

1. A mortising machine including upper and lower bearing blocks, the lower block being bifurcated, a pulley having stub axles 90 movable in the bifurcated portions, adjusting bolts engaging the said axles, a connecting rod between the bearing blocks, a pulley on the upper block, a supporting bar having an opening for receiving the connecting 95 rod, a spring disposed between the supporting bar and the upper block for forcing the supporting bar normally outwardly, a belt applied to the pulleys the belt having cutting knives, and supporting legs pivoted to the 100 ends of the supporting bar said legs being capable of adjustment by reason of the pivotal connection for regulating the tension of the spring when the mortising machine is applied to the work.

105 2. In a mortising machine, spaced bearing blocks having pulleys rotatably carried thereby, an endless belt passing over said pulleys, cutting knives mounted upon the outer surface of said belt, a bar, a rod connecting said bearing blocks slidably mounted in the bar, supporting legs pivotally connected to said bar, a spring wound about said rod and engaging said bar and one of said blocks for normally holding said cutting knives out of engagement with the timber to be mortised.

110 In testimony whereof I affix my signature in presence of two witnesses.

ERNEST RIEDER.
